CALCULATING MACHINE

Mario Bellini, Milan, Italy, assignor to Ing. C.
Olivetti & C., S.p.A., Ivrea, Italy

Filed Apr. 25, 1966, Ser. No. 2,012

Term of patent 14 years

(Cl. D64—11)

Fig. 1

Fig. 2

FIG. 1 is a front perspective view of a calculating machine showing my new design;

FIG. 2 is a rear perspective view thereof.

The essential features of the design reside in the portions shown in solid lines, the conventional keys being shown in broken lines.

I claim:

The ornamental design for a calculating machine, substantially as shown and described.
